UNITED STATES PATENT OFFICE.

CLINTON W. RUSSELL, OF DETROIT, MICHIGAN.

DUMP-CAR.

No. 918,092.

Specification of Letters Patent. Patented April 13, 1909.

Application filed March 3, 1908. Serial No. 418,986.

To all whom it may concern:

Be it known that I, CLINTON W. RUSSELL, a citizen of the United States of America, residing at Detroit, in the county of Wayne 5 and State of Michigan, have invented certain new and useful improvements in Dump-Cars, of which the following is a specification, reference being had therein to the accompanying drawings.

10 The invention relates to railway dumping cars, and consists in the novel construction of mechanism for operating the sides of the car, as more fully hereinafter set forth.

In the drawings—Figure 1 is a perspective 15 view of the car in normal position; Fig. 2 is a similar view illustrating the operation of dumping; and Fig. 3 is a diagrammatic view showing the operation of the mechanism.

A is a railway dump car, of any suitable 20 construction but which, as shown, is provided with a frame B having arranged centrally thereof the pivot bearings C for supporting the box body.

D are rockable supports for engaging the 25 bottom of the body upon opposite sides of the central pivotal support, and which may be adjusted to permit the tilting of the body in dumping the load.

To permit the discharge of the load when 30 the body is tilted the sides E of the body are removable and mechanism is provided for automatically operating the same. This mechanism comprises a system of links and levers so arranged that as one edge of the 35 body is lowered, the side member thereof is raised and moved into a position which is substantially parallel to the bottom of the body when completely tilted.

In detail F is a link which is pivotally attached at one end to the end of the side or door E near the bottom edge thereof, the opposite end of said link being pivotally attached at G to the center of the end H of the body and near the upper edge thereof.

45 I is a strut rod pivotally attached to the link F intermediate its ends and extending downward, the lower end being attached to a link J. This link is pivotally attached at its inner end K to the frame B, while the outer end is adapted to rest upon the bearing L on said frame.

M is a second link pivotally attached to the end of the side or door E and near the upper edge thereof. This link is pivotally 50 attached to a coöoperating link member

which, as shown, is formed by a member N secured to the strut rod I and projecting laterally therefrom. The pivotal connection between the members M and N is so located that in the closed position of the door E 60 this pivot is in line with the pivots a and b which respectively connect the rod I with the link F and the link M with the door E. Thus the members M and N together form a pair of toggles, which are straightened out 65 in the closed position of the door so as to form a rigid link.

With the construction as described whenever the car body is tilted in either direction the strut rod I upon the side of the body 70 which is lowered will hold the link F from lowering with the body. At the same time, the strut rod I is free to swing so as not to interfere with the movement of the inner pivotal end G of the link F, the result being 75 that the door is swung outward and upward as the body moves downward. The change in angularity of the link F and strut rod I will cause a partial folding of the toggle members M and N, which will shorten the 80 distance between the pivots a and b, and this will result in throwing inward and downward the upper edge of the door E until the latter is arranged in parallelism with the bottom of the body. During the movements just de- 85 scribed, the strut rod I on the upwardly moving side of the car will be raised, but this movement will be permitted by the upward swinging of the link J without producing any alteration in the relative positions of the 90 links F and the members M and N which are connected to the door on that side. The freedom for upward movement of the strut rod I may also be employed for raising the door at any time without tilting the body. 95

What I claim as my invention is:

1. The combination with a car body, of a removable door or side thereof, a pair of pivotal links for connecting the end of said door to the end of the body, one of said links 100 being formed of a pair of toggle levers which are straightened in the closed position of the door and are foldable as the door opens, and both links forming rigid ties for resisting lateral stresses on the door when in closed 105 position.

2. The combination with a car body, of a door forming one side thereof, a pair of pivotal links for connecting the end of said door with the end of said body, one of said 110

links being formed of foldable sections or toggles, said toggles being straightened in the closed position of the door and being pivotally connected at one end to the other link.

5 3. The combination with a car body, of a door forming one side thereof, a pivotal link extending between the end of said door near the lower edge thereof and the end of the body near the center of the upper edge thereof, and a foldable sectional link connecting the end of the door near the upper edge thereof, and a point intermediate the ends of the first mentioned link, said foldable link being straightened in the closed position of

15 the door.

4. The combination with a tilting car body, of a door at one side thereof, a pivotal link connected to the end of the door near the lower edge thereof and inclining upward 20 toward the center of the end of the body to which it is attached, a rockable strut connected to said link and having a fixed bearing for its lower end and a foldable sectional link connecting the end of said door near the upper 25 edge thereof with said first mentioned link, one of said sections of said foldable link being rigid with said strut.

5. The combination with a tilting car body, of a door at one side thereof, a pivotal link connected to the end of said door near

the lower edge thereof and inclining upward therefrom to the pivotal connection with the end of the body, a rockable strut having a fixed supporting bearing for its lower end and pivotally connected to said link intermediate the ends of the latter, a lateral extension rigid with said strut, and a link pivotally connected to said lateral extension and the end of said door near the upper edge thereof, for the purpose described.

6. The combination with a tilting car body, of a door at one side thereof, a pivotal link connected to the end of said door near the lower edge thereof and extending inward to its point of pivotal connection with the end of said body, a rockable strut having a fixed bearing for its lower end and pivotally connected to said link intermediate the ends of the latter, a foldable link extending between said strut and the end of said door near the upper edge thereof, the said parts being proportioned to move said door into substantial parallelism with the bottom of said body when the latter is tilted.

In testimony whereof I affix my signature in presence of two witnesses.

CLINTON W. RUSSELL
